APPARATUS FOR MOISTENING GUMMED ARTICLES

Commodore D. Ryan, Los Angeles, Calif., assignor to Commercial Controls Corporation, a corporation of Delaware

Original application April 29, 1940, Serial No. 332,305. Divided and this application September 27, 1941, Serial No. 412,543

8 Claims. (Cl. 91—43)

This invention relates to an envelope flap moistening device for use in a mail treating machine or other envelope treating device.

One of the objects of this invention is to provide an envelope flap moistening device characterized by simplicity, sturdiness, and capable of extended efficient operation. Another object is to provide a device of the above nature capable of uniformly moistening the gummed flap of an envelope or the like throughout the extent of the gummed portion thereof. Another object is to provide a device of the above nature capable of adjustment with respect to the article being moistened so as to control the extent to which such article is moistened. Another object is to provide a device of the above nature capable of closely engaging the envelope flap of the article being moistened. Another object is to provide a device of the above nature capable of moistening substantially all shapes of envelope flaps at high speed without wrinkling, buckling, catching, or tearing. Other objects will be in part apparent and in part pointed out hereinafter.

The invention accordingly consists in the features of construction, combinations of elements, and arrangements of parts as will be exemplified in the structure to be hereinafter described and the scope of the application of which will be indicated in the following claims.

This application is a division of the application of Frank P. Sager, Ernest R. Bergmark, Commodore D. Ryan and Herschel L. Atherton, Serial No. 332,305, filed April 29, 1940.

In the drawings wherein there is shown one form of my invention,

Figure 1 is an enlarged fragmental sectional view of the moistening device.

Figure 2 is an enlarged view of the moistening blade shown partially in vertical sections to illustrate the construction of the interior thereof.

Figure 3 is a horizontal sectional view taken along the line 3—3 of Figure 1.

Figure 4 is a sectional view taken along the line 4—4 of Figure 5 to show the means for adjusting the position of the envelope flap guiding blade; and,

Figure 5 is a fragmentary sectional view taken along the lines 5—5 of Figure 4, a portion thereof being broken away to show the structure by which the envelope flap guiding plate is mounted.

Similar reference characters refer to similar parts throughout the several views of the drawings.

In order that certain salient features of my invention may be more clearly understood, it

might be well first to point out that mail treating machines of the character shown in the above noted application are desirably of a nature capable of handling a large number of envelopes per unit of time. For example such a machine may be called upon to seal and stamp as many as ten thousand envelopes per hour, and to attain this high capacity the envelope flap moistening and sealing devices must function with a high degree of efficiency regardless of the size and shape of the envelope flap being moistened and without in any way damaging the envelope. Most envelope flap moisteners of the character under consideration are unsuitable for this type of work because of their inability to apply the right amount of moisture on the gummed portion of the envelope flap where such a large number of envelopes are handled without becoming clogged with glue or so gummed up as to become unable to apply sufficient moisture for softening the adhesive on the envelope flap. It is accordingly another object of this invention to provide a moistening device of the above nature capable of overcoming such difficulties.

Referring now to Figures 1 and 3, the envelope flap moistening device is generally indicated at 154 and includes a removable element (Figures 1 and 2). As shown in Figure 2, removable element 387, i. e. the moistener blade, includes a handle portion 388 and a blade portion 389 secured to said handle in any suitable manner as for example by screws 390. The moistening blade 389 extends outwardly from the handle and is provided with a fluid passage 391 communicating with the fluid passage 392 formed in the handle portion 388. The blade portion 389 is tapered as shown in Figure 2 and has a transverse cross section, generally of the shape as shown in Figure 4. It will be understood that the cross section gradually becomes flatter as the outer end of the blade is approached. The blade is provided with a suitable cover 393 to enclose passage 391. The underside of the blade is provided with a capillary moistening slot 394 which slot has a greater depth at the handle end of the blade and gradually tapers to a minimum depth at the point thereof.

Referring to Figure 2, it may be observed that the top surface of the moistening blade is substantially horizontal, while the under-surface thereof tapers from a relatively thick section adjacent the handle or heel end of said blade to a relatively thin section at the point thereof. Due to this inclination, the fluid would tend to

flow more freely from the lower heel end of the capillary moistening slot 394 and to counteract this tendency, the capillary slot is deeper at its heel end and gradually tapers to a minimum depth at the point end of the blade, thereby substantially equalizing the feed of the moistening fluid throughout the entire length of said capillary slot. This tendency to equalize the feed of fluid results from the greater friction or resistance to the flow of fluid through the deeper portion of the slot than through the shallower depth thereof.

In order to facilitate the control of the flow of sealing fluid through the capillary slot, a relatively small twisted wire 395 may be mounted 15 within the blade to overlie the capillary slot 394. The inner end of wire 395 is bent downwardly to extend into the fluid passage 392 and is provided at its end with a small globule of solder 396 to maintain the wire properly positioned within the blade and to assist the insertion and removal of said wire from the blade for cleaning purposes when the blade is removed from its handle portion 388. This twisted wire 395 effects 20 the flow of fluid into the moistening blade and through its slot as the fluid is drawn along the blade by capillary attraction and accordingly delivered thereby uniformly to the slot substantially throughout the entire length thereof. The fluid passage 392 formed in the handle portion 388 is provided at its entrance end with a counter bore 397 into which is positioned a sealing washer 398. The moistening element 387 may be easily and conveniently disassembled from the machine for the purpose of cleaning and as readily reassembled. For this purpose the machine is provided with a suitable holder 399 which is preferably formed of a casting having lugs 400 for screws 401 by means of which the holder is rigidly fastened to the frame bracket 250 (Figures 1 and 3). The holder extends forwardly from its point of support and projects through a rectangular opening 402 (Figures 1 and 3) formed in the front plate 160 of the main frame of the mail treating machine. The front end of the holder is provided with a lug 403 against which a flange 404 is securely fastened by means of screws 405. A sealing gasket 406 is interposed between lug 403 and flange 404 and the flange 404 may be also secured to the front plate 160 by means of screws 407. The body portion of holder 399 is generally box shaped as shown in Figures 1 and 3 and is provided at its forward end with a rectangular opening 408 of such size as to slidably receive the rectangular body portion of the moistening element 387 and is provided adjacent its inner end with an aligned but smaller rectangular opening 409 to receive the blade portion of the moistening element 387 adjacent the fluid inlet passage 392 of the moistening element 387. The holder 399 is provided with an end wall 410 against which the sealing washer 398 is maintained in sealing engagement by means later to be described.

The end wall 410 is provided with a fluid inlet passage 411 (Figure 1) which registers with the inlet passage 392 of the moistening element when the latter is mounted in its operative position in said holder. The holder is provided with a rearwardly extending portion 412 through which the inlet passage 411 is drilled and at the rear end of this portion of the holder, the inlet passage is enlarged to receive the end of inlet pipe 413 which may be soldered therein to provide a fluid tight connection between the pipe and holder.

The box like portion of the holder is provided with a drain passage 414 (Figure 1) to drain the holder of such fluid as may enter therein during the removal of the moistening element 387.

Means are provided for releasably maintaining the moistening element 387 within the holder so that its washer 398 is maintained in fluid tight relation with the end wall surface 410 of said holder. This means may include a pair of links 415 carrying between the free ends thereof a roller 416 engageable with an arcuate depression 417 formed in the moistening element handle portion 388. The opposite ends of said links are pivotally connected to the head end of rod 418 slidably extending through lug 403 of said holder. The slide rod 418 is provided on its inner end with a compression spring 419 which acts between lug 403 and washer 420 suitably maintained upon the rear end of said rod by means of cotter pin 420a.

To remove the moistening element 387, the operator need only swing the links 415 downwardly to free roller 416 from the handle portion 388 thereby releasing the moistening element for removal. The tension spring 419 provides the necessary give to permit the roller to roll out of the depression 417. A pin 421 interconnects links 415 intermediate their ends to engage shoulder 422 formed upon the inner surface of the handle portion of the moistening element to act as a stop for locating the roller 416 in registration with the depression 417 when locking said element in its operative position.

As may be observed in Figure 3, the envelope conveyor plate 165 overlies the top surface of holder 399 and acts to not only close the top surface of the holder, but also to maintain the moistening element within said holder. The top surface of the moistening element 387 closely engages the undersurface of the envelope conveyor plate 165 (Figure 1) to prevent the flaps of the envelopes from passing between said element and plate.

Guide means are provided for directing the flaps of the envelopes across the capillary slotted portion of the moistening blade. This means may include a wedge shaped block 423 fastened to the intermediate frame plate 161 by means of screws 424, clamping between said block and said plate the latter guide plate 170. The wedge block 423 is shaped as shown in Figures 3 and 4 and acts to start the folding movement of the downwardly hanging flaps of those envelopes to be sealed and to further assist the block in its folding action, especially when treating envelopes having deep flaps, a pin 425 extends from said block at an angle directed toward the moistening blade 389 in the manner shown in Figure 3. A guide plate 426 receives the envelope flaps as they ride over the wedge shaped block 423 and pin 425 and acts to direct the flaps of the envelopes under the moistening blade 389 in the manner shown in Figure 4. To press the gummed surface of the envelope flap against the capillary slot 394 of the moistening blade, a spring plate 427 engages the envelope flap as it leaves the moistening blade. As shown in the drawings, the moistening blade 389 overlies the space formed between the trailing edge of guide plate 426 and the flap engaging surface of spring plate 427. In order to insure the entrance of the flaps under the sealing blade 389, the blade is tapered as shown in Figures 1 and 2 so that its forward end is slightly above the flap engaging surface of plates 426 and 427 and as the blade tapers toward its handle end, it extends down into the space provided between these

two plates thereby causing the envelope flap to be depressed so that its gummed surface will closely hug the capillary slot portion of the moistening blade.

Guide plate 426 and spring plate 427 are securely mounted upon opposite faces of a rectangular adjusting block 428. The adjusting block 428 is mounted between frame bracket 250 (Figures 3 and 5) and the intermediate frame plate 161 by means of eccentric shaft 429 and pivot screw 430 (Figure 5). The block is provided with a forwardly extending lip 431 (Figures 3 and 4) to form with the horizontal portion of spring plate 427, a groove in which is positioned an eccentric bushing 432 which bushing is journaled upon the eccentric shaft 429. Through the rotation of eccentric bushing 432 by means of a spanner wrench engaging pin holes 433 formed in the forward end of this bushing, the adjusting block 428 will be rocked to adjust the relation of the guide and spring plates with respect to moistening blade 389. After the adjusting block has been rocked to properly locate the guide and spring plates, it may be locked in its adjusted position by tightening both, pivot screw 430 and eccentric shaft 429, which shaft is screw threaded into plate 161. As shown in Figure 5, the inner end of adjusting block 428 is provided with a bearing plate 434 having a hole through which the eccentric shaft passes. The bearing plate 30 hole is of sufficient size to provide for the necessary movement of said block during its adjustment, but not large enough to permit the eccentric bushing to extend therein. The bearing plate 434 acts to support the block with its assembled plates while being adjusted in the manner described and is clamped between the eccentric bushing and the envelope guide plate 170 when the eccentric shaft is screwed into plate 161 to thereby securely lock the bearing plate end of the assembly. The spring plate 427 may be slotted as at 435 to provide for greater flexibility and to divide the free end of the plate into two sections whereby these sections may be independently formed or bent to properly guide the envelope flaps under the moistening blade.

The envelope flap guide plate assembly in combination with the particular form of moistening blade comprises one of the important features of this invention as this organization enables the moistening of shallow, deep, angled or square flaps without need of adjustment after once having been set in operative position and is efficient in its operation upon all of the above mentioned shapes and sizes of envelope flaps and will permit the passing of the flaps through the moistening organization at high speed without wrinkling, buckling, catching, tearing.

Another feature of this assembly resides in the adjustability of the guide and spring plates to control the amount of water to be deposited upon the gummed surface of the flap passing across the capillary slot of the sealing blade. The guide and spring plate adjustment as shown in Figure 4 is set for normal operation, but should a greater amount of water be desired on the gummed surface of the envelope flap, the pivot screw 430 and shaft 429 may be loosened and the eccentric sleeve 432 rotated in the manner described to swing the assembly in a clockwise direction as viewed in this figure about pivot screw 430 to lower the flap engaging surface of spring plate 427 thereby permitting the flap to leave the moistening blade at a flatter angle so that a

greater amount of water may be deposited upon the gummed surface as it leaves the capillary slot. Upon setting the flap guiding assembly to deposit the desired quantity of water, it may be locked in the adjusted position by tightening the eccentric shaft and pivot screw in the manner previously described. If too much water is deposited upon the gummed surface of the envelope flap, the assembly may be adjusted in the reverse direction. In this manner the amount of water deposited upon the gummed surface of the envelopes may be accurately controlled.

Thus I have provided an envelope flap guide and moistening plate which attains in a thoroughly efficient manner the several objects set forth hereinabove.

I claim:

1. In a blade for moistening the adhesive portion of envelope flaps, said blade being formed with a tapered portion and having a fluid passage extending along the taper of said blade and having an angular entrance passage, a flap engaging surface formed along the underside of said blade, a capillary fluid feeding slot communicating said surface with said passage, and an intertwined metallic member mounted within said passage overlying said slot and having an angularly related weighted end extending down into said entrance passage.

2. In a device for moistening the adhesive surface of envelope flaps, a moistening blade across which the gummed surface of the flaps are drawn for moistening, means for guiding the envelope flaps to said blade, and means directing the flaps as they leave said blade, means for mounting said guiding and directing means for simultaneous movement, and means adjusting said mounting means to simultaneously increase the angle of approach and decrease the angle departure of the envelope flaps passed through said device for controlling the amount of fluid deposited upon the gummed surface thereof.

3. In an envelope sealing machine, a frame, a fluid conveying means carried thereby having a ported surface, a removable moistening blade disposed above said conveying means and having a ported surface on its underside for registration with the port surface of said fluid conveying means, and means for maintaining said surfaces in sealing engagement.

4. In an envelope sealing machine, a frame, a fluid conveying means carried thereby having a ported surface, a removable moistening blade disposed above said conveying means and having a ported surface on its underside for registration with the port surface of said fluid conveying means, and means yieldingly maintaining said surfaces in sealing engagement.

5. In a blade for moistening the adhesive portion of an envelope flap or the like, in combination, means forming a fluid passage in said blade, said blade having a flap engaging surface, means forming a capillary fluid feeding slot extending from said surface to said passage and an elongated wire positioned within said passage overlying said slot and in engagement with the edges of said slot at spaced portions thereof for controlling the flow of fluid thereto.

6. A device for moistening the adhesive portion of an envelope flap or the like comprising, in combination, a moistening blade across which the gummed surface of the envelope flap is drawn for moistening, means for guiding the envelope flap to said blade, means for directing the flap as it leaves said blade, means for mounting said

guiding and directing means for movement upwardly and downwardly of the path of the envelope flap past said blade, and means for adjusting the vertical positions of said guiding and directing means for controlling the angles of approach and departure of the envelope flap as it passes through said device to control the amount of fluid disposed upon the gummed surface thereof.

7. In a blade for moistening the adhesive portion of an envelope flap or the like, in combination, means forming a fluid passage in said blade, said blade having a flap engaging surface, means forming a capillary fluid feeding slot extending from said passage to said surface and being substantially coextensive longitudinally with said surface, and an elongated stationary member dis-

posed within said passage and overlying said slot and having an uneven surface engaging portions of the edges of said slot to control the flow of fluid thereto.

8. In a blade for moistening the adhesive portion of an envelope flap or the like, in combination, means forming a fluid passage in said blade, said blade having a flap engaging surface, means forming a capillary feeding slot in said platen extending from said passage to said surface, an elongated member loosely mounted within said passage and overlying said slot and engaging the edges thereof at spaced portions, and means for maintaining said member in stationary operative position within said passage over said slot.

COMMODORE D. RYAN.
